W. L. ASHMORE & W. T. MORGAN, JR.
PROCESS AND DEVICE FOR FINISHING CONCRETE PAVEMENTS.
APPLICATION FILED MAR. 27, 1916.

1,273,022.

Patented July 16, 1918.

UNITED STATES PATENT OFFICE.

WALTER LORENZO ASHMORE AND WILLIAM T. MORGAN, JR., OF MACON, GEORGIA; SAID MORGAN ASSIGNOR OF TWO-SIXTHS OF THE WHOLE RIGHT TO H. R. POWELL, OF BIBB COUNTY, GEORGIA.

PROCESS AND DEVICE FOR FINISHING CONCRETE PAVEMENTS.

1,273,022.

Specification of Letters Patent. Patented July 16, 1918.

Application filed March 27, 1916. Serial No. 87,099.

To all whom it may concern:

Be it known that we, WALTER L. ASHMORE and WILLIAM T. MORGAN, Jr., citizens of the United States, and residents of Ma- 5 con, in the county of Bibb and State of Georgia, have invented certain new and useful Improvements in Processes and Devices for Finishing Concrete Pavements, of which the following is a specification.

10 Our invention relates to improvements in devices for finishing and smoothing concrete or cement pavements, and it consists in the combinations, constructions, and arrangements herein described and claimed.

15 An object of our invention is to provide a roller which is applied directly to the surface of the walk or pavement in contrast with strike boards or templets formerly used.

20 A further object of our invention is to provide a process by means of which the building of cement sidewalks or roadways may be effected at a considerable economy.

25 A further object of our invention is to provide a device which will evenly distribute the cement mortar and make it more compact, thereby obviating check cracks in the pavement.

30 Other objects and advantages will appear in the following specification, and the novel features of the invention will be particularly pointed out in the appended claims.

Our invention is illustrated in the accompanying drawings, forming part of this application, in which:

35 Figure 1 is an end view of the device.

Fig. 2 is a front view.

Fig. 3 is a perspective view of a portion of the device.

40 Fig. 4 is a sectional view through the end of the device.

Before describing one specific form of the invention, it may be well for us to state that the device is designed to be used on freshly laid oversaturated concrete which is in a 45 soft jellylike or plastic condition. Many times in mixing the batches and in spreading the plastic mass, one part will be of a denser nature than another; one part will be softer than another only a few inches apart. Then again one part of the surface will have a preponderance of coarse aggregate, and another too much mortar; or again, there will be a high place, or a low

place on the surface. If the surface has been struck off with a strike board or 55 templet, the surface is apt to show high over each piece of coarse aggregate and low between them.

We make use of a roller to overcome these objections, this roller being of relatively 60 light material and being arranged to float on the plastic concrete mass. The roller is, therefore, closed at both ends, so as to prevent the entrance of water or any of the plastic mass. The rollers are made in sets, 65 each roller being long enough to act on the surface as a straight edge, and, as stated, must be light, so that it will not sink down in the concrete. Light material, such as thin iron, steel, or other metal, such as papier 70 maché, hard rubber, or like material, made hollow and water tight, may be used for these rollers.

Referring now to Fig. 2, our improved 75 roller which is denoted by the numeral 1 consists preferably of a hollow steel cylinder, which is of small diameter and comparatively great length, being only a few inches in diameter and preferably from 7 to 10 feet in length, so as to adapt it to extend 80 over several high or low places, or both, and very light, so that it will float on freshly laid soft plastic concrete and act as a straight edge in smoothing out and straightening the uneven surface. At each end of 85 the cylinder 1 is disposed a wooden block 2 which is fastened securely by any suitable means, and which is provided with a central bore 3 arranged to receive a stub shaft 4 which, in this instance, consists of a bolt 90 whose head 5 is on the inner side and whose threaded portion 6 is on the outer side of the block 2.

The bail members 7 and 8 are formed of 95 light pressed steel channel irons, of U-shaped cross section. At the end of each of these bail members is disposed a steel block, such as that shown at 9 in Fig. 3, which is provided with a bore 10 arranged to receive a brass bushing 11 which is threaded internally.

In securing the handle to the device, the washers 12, the nut 13, and the washer 14, see Fig. 4, are first placed on the threaded end of the shaft 4, the threaded bushing 11 105 is placed on the threaded portion 6 of the

shaft, and the bail member 7 with the steel block secured in place is then brought into position, after which a washer 15 and a nut 16 are placed on the end of the shaft.

- 5 A handle 17 is provided which is secured to the bail members 7 and 8, preferably by means of bolts and winged nuts 18, so that handles of different lengths may be used by removing the handle members from the bail 10 members 7 and 8, and replacing with others of various lengths.

The use of a roller of this kind for smoothing concrete pavements, renders the cost of finishing less, and more evenly distributes the concrete mortar and renders it 15 more compact, thus obviating check cracks in the concrete pavement.

From the foregoing description of the rollers, the process of finishing the walk, 20 may be readily understood. As stated before, each roller is long enough to act on the surface as a straight edge, and is light so that it will not sink down into the concrete. The long roller is run over the surface first 25 to straighten it and equalize an overwet or dry spot, and to sink the coarse aggregate to an equal depth with the mortar and to condense the mass. Then a short light roller of the same construction as the long roller 30 but shorter and lighter, by reason of its length, is run over the surface to evenly spread any excess mortar and to further smooth the surface and to condense and pack it to fill the air and water voids in the body 35 and surface of the paving. When the oversaturated concrete as used in road making is spread upon the road bed as it comes from the mixing machine there are necessarily high and low places, and by rolling the same 40 with a roller of the described construction, moved backward and forward at different angles, and adapted to float on the concrete and act as a straight edge in smoothing out and straightening the surface, a constant 45 agitation of the concrete mass is effected, causing the heavy particles, such as bits of stone, to settle down, and also reducing the high places and filling the low places, and at the same time the lighter particles, that 50 is, sand, cement and water are caused to rise to the surface, and the entire mass of the concrete is brought to a uniform body surface, with the heavier particles shaken down or caused to settle while the lighter particles 55 are caused to rise to the surface, which is thus made smooth; and by such agitation and vibration, as the heavier particles settle down and the hollow places become filled, water is forced to the surface and any excess 60 water is allowed to flow off. Shortly after treatment with the long floating roller, and while the concrete is still in a soft plastic state, it is further treated by rolling with a shorter and therefore lighter floating roller 65 which is moved at different angles in all di-

rections across or over the surface of the concrete, thereby further smoothing the surface and eliminating any excess water.

We claim:—

1. A device for finishing and smoothing 70 concrete pavements and the like, which consists of a hollow cylindrical roller, wooden blocks secured in the ends of said roller, each of said blocks having a central bore, a bolt disposed in each bore, the head of the bolt 75 being on the inside of the block, a pair of bail members, said bail members being made of channel iron and being U-shaped in cross section and each of said bail members having an opening for receiving the end of the bolt, 80 a steel block disposed between the arms of said channel irons, said blocks being provided with a cylindrical bore, a brass bushing arranged to enter said cylindrical bore, and being threaded internally to receive the 85 threaded end of said bolt, and means including a nut on each side of said channel irons for holding the channel irons in position with respect to the end of the roller.

2. A device for finishing and smoothing 90 concrete pavements and the like, which consists of a hollow cylindrical roller, wooden blocks secured in the ends of said roller, each of said blocks having a central bore, a bolt disposed in each bore, the head of the 95 bolt being on the inside of the block, a pair of bail members, said bail members being made of channel iron and being U-shaped in cross section and each of said bail members having an opening for receiving the 100 end of the bolt, a steel block disposed between the arms of said channel irons, said blocks being provided with a cylindrical bore, a brass bushing arranged to enter said cylindrical bore and being threaded internally to receive the threaded end of said 105 bolt, and means including a nut on each side of said channel irons for holding the channel irons in position with respect to the end of the roller, said bail members being bent into Z-shaped form, and a common handle secured to said bail members.

3. A device for finishing and smoothing 115 concrete pavements and the like, which consists of a hollow cylindrical roller, wooden blocks secured in the ends of said roller, each of said blocks having a central bore, a bolt disposed in each bore, the head of the bolt being on the inside of the block, a pair of bail members, said bail members being 120 made of channel iron and being U-shaped in cross section and each of said bail members having an opening for receiving the end of the bolt, a steel block disposed between the arms of said channel irons, said blocks being provided with a cylindrical bore, a brass bushing arranged to enter said cylindrical bore and being threaded internally to receive the threaded end of said bolt, means including a nut on each side of said 125 130

- channel irons for holding the channel irons in position with respect to the end of the roller, said bail members being bent into Z-shaped form, and a common handle secured to said bail members, said securing means being adjustable to permit the removal of the handle and the substitution of another handle. 5
4. In a device for smoothing and finishing cement walks, pavements, and the like, the combination with a roller having a stub shaft at each end, of a pair of bail members, said bail members being made of channel iron and being U-shaped in cross section, one end of each of the bail members having an opening for receiving the ends of the shaft, a steel block disposed between the arms of the channel iron, said block being secured to said channel iron and being 10 provided with a cylindrical bore, a brass bushing arranged to enter said cylindrical bore and being threaded internally to receive the end of the shaft, and means including a nut on each side of said channel iron for holding the channel iron in position with respect to the end of a roller. 15
5. A device for finishing concrete pavements and the like, consisting of a hollow liquid-tight roller of small diameter and
- comparatively great length and light weight 30 adapted to float on freshly laid plastic concrete and to act on the surface thereof as a straight edge for straightening and smoothing such surface.
6. The herein described method of finishing concrete pavements and the like, which consists in rolling the surface of freshly laid soft plastic concrete with a roller of small diameter and comparatively great 35 length and light weight adapted to float on the soft plastic concrete and to act on the surface thereof as a straight edge for straightening and smoothing the surface of the concrete mass and eliminating any excess water. 45
7. The herein described method of finishing concrete pavements and the like, which consists in rolling the surface of freshly laid soft plastic concrete with a roller of small diameter and comparatively great 50 length and light weight adapted to float on the soft plastic concrete and to act on the surface thereof as a straight edge, and subsequently rolling the same with a shorter and proportionately lighter floating roller 55 to further smooth and finish such surface.

WALTER LORENZO ASHMORE.
